UNITED STATES PATENT OFFICE.

ARTHUR W. SMITH, OF NEW YORK, N. Y., ASSIGNOR TO REMINGTON TYPEWRITER COMPANY, OF ILION, NEW YORK, A CORPORATION OF NEW YORK.

TYPE-WRITING MACHINE.

1,147,981.

Specification of Letters Patent. Patented July 27, 1915.

Application filed January 27, 1914, Serial No. 814,633. Renewed January 28, 1915. Serial No. 4,963.

To all whom it may concern:

Be it known that I, ARTHUR W. SMITH, citizen of the United States, and resident of the borough of Manhattan, city of New York, in the county of New York and State of New York, have invented certain new and useful Improvements in Type-Writing Machines, of which the following is a specification.

10 My invention relates to typewriting machines and more particularly to tabulating mechanism for such machines.

The present invention is in the nature of an improvement on the construction disclosed in my application, Serial No. 730,350, filed November 9th, 1912.

One of the objects of the present invention, generally stated, is to provide means whereby in addition to the results obtained 20 by my prior construction I may readily obtain denominational selection in the different selected columns.

A further object of the invention, considered from a somewhat different aspect, is to provide improved means by which the denominational selecting mechanism may at 25 will be rendered inoperative or ineffective for denominational selection, so that the column selecting mechanism may be used 30 as such indefinitely and without any interference from the denominational selecting means.

Another object of my invention is to provide improved means by which, in a single 35 line of writing, for example, tabulation only from one column to the next may be obtained at one portion of the line; in which denominational selection may be obtained at another portion, or at other portions, of a 40 line; in which column selection may be obtained; and in which when desired denominational selection within selected columnar fields may be obtained.

To the above and other ends which will 45 hereinafter appear, my invention consists of the features of construction, arrangements of parts and combinations of devices set forth in the following specification and particularly pointed out in the appended claims.

50 In the accompanying drawings wherein like reference characters designate corresponding parts in the various views, Fig. 1 is a side elevation with parts in section of one form of typewriting machine embody-

ing my invention, only so much of the machine being shown as may be necessary to illustrate my invention in its embodiment therein. Fig. 2 is a fragmentary detail perspective view showing a portion of the connections between the column-to-column tabulator key and the carriage releasing means. Fig. 3 is a top plan view, with parts sectioned away, of a portion of the tabulator mechanism and some of the associated parts. Fig. 4 is a fragmentary top plan view of the 65 machine showing a work sheet in place in the machine. Fig. 5 is a detail top plan view of the key controlled column-to-column stop and some of the associated parts.

I have shown my invention, in the present 70 instance, embodied in a No. 11 Remington machine, although a simplified showing of some of the parts has been included and features of the construction have been modified to fit the requirements of the present invention. It should be understood, however, 75 that the invention may be embodied in various styles of typewriting machines and that various changes may be made accordingly.

The frame of the machine comprises a 80 base 1, corner posts 2 and a top plate 3. Fixed oppositely grooved guide rails 4 are secured to the top plate and receive anti-friction balls or rollers 5 in the grooves 85 therein. Said rollers are also received in oppositely grooved guideways 6 formed in front and rear rails 7 and 8, respectively, of the carriage, which is designated as a whole by the reference numeral 9. A cylindrical platen 10 is supported in bearings in a platen 90 frame 11, the latter being connected by parallel links 12 to the carriage in order to afford a vertical case shifting movement of the platen. The usual upwardly and rearwardly swinging segmentally arranged type 95 bars 13 strike against the front face of the platen. The platen frame carries a grooved roller 14 which bears upon a shift rail 15. This shift rail is connected to depending links 16 united by a cross bar 17. Depending arms 18 and 18^a project from the cross bar 17, the depending arm 18^a being connected to a shift lever 19 provided with a shift key 20 arranged at the keyboard of the machine. The depending arm or link 100 18 is connected to a shift lever 21 which is provided at the keyboard of the machine with a shift key 22. The shift levers 19

and 21 are pivoted to turn on a fixed pivot rod 23. These shift levers are united by a cross bar 24 which is provided at each end thereof with an outwardly projecting pin 25 to which one end of a contractile spring 26 is connected, the opposite end of each spring being connected to a depending pin 27 (see Fig. 1) which is secured to the base of the machine in a manner to be hereinafter described. The springs 26, which are operative to counteract the weight of the platen, afford an easy ease shifting movement thereof under the control of the shift keys. This ease shift mechanism is of the ordinary construction, but is specifically described herein because of its co-operation with other parts to be hereinafter referred to.

The carriage is moved by a spring drum 28 having one end of a band 29 connected thereto, the opposite end of said band being connected to a bracket 30 secured to the right-hand end portion of the carriage. The carriage is moved by the spring drum under control of the usual escapement mechanism, comprising escapement wheels 31 fixedly connected to the rear end portion of a shaft 32 which turns in a bearing member 33 secured to the top plate of the machine. The forward end of the shaft is provided 30 with a feed pinion 34 with which a feed rack 35 meshes. The feed rack is connected at its ends to forwardly projecting arms 36 which are pivoted at 37 to upwardly projecting ears or lugs 38 secured to the rear cross bar 35 of the carriage. Thus each of the lugs 38 is formed as a part of a bracket 39 which is secured to the rear carriage rail 8 by screws 40. The feed rack is thus pivoted to swing into and out of mesh with the feed pinion 34.

40 Each of the brackets 39, hereinbefore referred to, is provided with a rearwardly extending arm 41 to which a column stop bar 42 is secured. This column stop bar is provided with teeth on the front and rear sides 45 thereof for the reception of plate-like column stops in the spaces between such teeth. There are two sets of column stops on the bar, the stops of one set being designated by the reference numeral 43 and which stops 50 have their contact or engaging portions 44 projecting rearwardly from the column stop bar. Each of the other set of column stops is designated by the reference numeral 45, and each of such stops has its contact or engaging portion 46 projecting forwardly 55 from the column stop bar, so that the engaging portions of the column stops 43 travel in one path and the engaging portions of the column stops 45 travel in another path.

A series of key controlled stop carrying levers 47 is pivoted intermediate the ends thereof, as at 48, to a tabulator frame 49. The upper end portions of these stop levers 65 are bent forwardly to provide denomina-

tional stops 50 which project through guide openings in a comb plate 51 secured to the tabulator frame 49. The denominational stops are spaced apart at letter space intervals in the usual manner and may be projected forwardly to co-operate with the column stops 43, each of said denominational stops moving forwardly in a single path and to a single given extent when it is brought into co-operative relation with a column stop. 70

The lower end portions of the stop carrying levers 47 are spaced apart at a plurality of letter space intervals, as shown in Fig. 3, each lever being received at its lower end portion in a guide slot 52 in a fixed supporting plate 53. The lower end portion of each stop lever 47 is connected to the rear end of a forwardly projecting push rod 54 which extends through a guide opening in a member 55. This member may be secured to the base 1 of the machine at the forward portion thereof by set screws 56 which are received in tapped openings in members 57 secured to the part 55. The parts 55 and 57 are spaced apart to receive the lower edge 80 of the forward cross bar of the base 1 of the machine and may thus be clamped to the base by the screws 56. The member 55 has depending projections 58 each of which is apertured to receive one end of a contractile 85 spring 59, the opposite end of each spring being connected to the stem of a set screw 60 threaded into a sleeve 61 which surrounds the associated push rod 54. The inner end of each set screw 60 bears against the associated push rod in order to hold the sleeve or collar 61 in a position to which it may be adjusted along its push rod. Each push rod is also provided with a yoke or collar 62 secured in its adjusted position along the 100 rod by a set screw 63. A transversely arranged bar 64 is connected at its ends to upwardly extending arms 65 which are pivoted on the pivot rod 23. This bar 64 is slotted at intervals throughout its length to receive, 105 the push rods 54 in said slots, the collars or yokes 62 on the rods bearing against the front face of the bar 64. A rearward movement of any push rod, by its tabulator key 54^a, is effective to move the cross bar 64 rearwardly. Each of the arms 65 is connected to a rearwardly extending link 66, which in turn is connected at its rear end to a depending crank arm 67. The arms 67 are fixed on a rock shaft 68, mounted at its ends on pivot screws 69 which are supported in the base of the machine. The rock shaft 68 is also provided with a crank arm 70 which extends forwardly and then upwardly and rearwardly, as shown in Fig. 1. The free 110 end of this crank arm is connected to an upwardly extending link 71 which in turn is connected at its upper end to a carriage release device or lever 72. This latter is pivoted at 73 to a bracket 74 secured to the top 115

120 of the machine. The upper end of the lever 72 is connected to a carriage release device or lever 72. This latter is pivoted at 73 to a bracket 74 secured to the top 125 of the machine. The upper end of the lever 72 is connected to a carriage release device or lever 72. This latter is pivoted at 73 to a bracket 74 secured to the top 130

plate of the machine. The forward end portion of this release lever extends beneath the feed rack 35 where the release lever is provided with a contact shoe 75 for engagement with the feed rack to lift the latter out of mesh with the feed pinion 34 and thus free the carriage from control of the escapement mechanism. It will be understood therefore that the actuation of any of the tabulator keys 54^a is effective to project the corresponding denominational stop 50 into the path of the column stops 43 and to simultaneously effect a release of the carriage. In order to return the releasing lever 15 or device 72 and the parts connected therewith to normal position, I have provided a depending crank arm 68^a on the rock shaft 68. This arm is connected to one end of a contractile spring 68^b, the other end of which 20 is connected to a suitable fixed point. This spring tends to turn the arm 68^a forwardly and to return the rock shaft 68 and the parts connected therewith to normal position.

I have provided key controlled means co-operative with the column stops 45 by which the carriage can be arrested in first one column and then the next so as to provide a column-to-column tabulating mechanism operable to control column-to-column tabulation at a given point or at given points in the travel of the carriage. The key controlled stop mechanism which co-acts with the column stops 45 is as follows: A single key controlled stop 76 is adapted to be turned into the path of the engaging portions 46 of the column stops 45. This key controlled stop is mounted on one end portion of a rock shaft 77 which is received in bearing openings in bracket arms 78. These arms project from a bracket plate 79 secured to the top plate of the machine by screws 80. This rock shaft is free to turn in its bearings and also to move longitudinally therein. A sleeve or collar 81 is secured to the rock shaft by a set screw 82 and is arranged between the bracket arms 78. A coiled expansion spring 83 bears at one end against the collar 81 and at its opposite end against the left-hand bracket arm 78 in order to force the shaft 77 longitudinally in its bearings to the right, as represented in Fig. 5. The longitudinal movement of the shaft in this direction is limited by a crank arm 84 (see Fig. 4) secured to one end of the rock shaft by a nut 85. The construction is such that when the stop 76 is projected into the path of the column stops 45 and one of the latter engages the stop 76, said stop 76, together with the rock shaft 77, will be moved by the power of the carriage to the left until further movement of the stop 76 is arrested by the complete compression of the spring 83 between the collar 81 and the left-hand bracket arm 78. The main object in shifting the stop 76 in the direction

of the feed of the carriage, at each tabulating operation under control of the stop 76, is to prevent a reengagement between the engaged column stop 45 and the stop 76. Thus it will be understood that after an arrest of the carriage has been effected by the co-operation of the stop 76 with one of the column stops 45, and the stop 76 turns with its shaft back to normal position, the spring 83 will displace the stop 76 toward the right, thus throwing it out of alignment with the previously engaged column stop 45 and preventing a reengagement with such column stop on the next actuation of the stop 76. It will be understood, of course, that incidentally there is a slight buffing action effected by the compression of the spring 83 at each tabulating operation under the control of the stop 76, so as to prevent undue shock or jar to the parts. 85

The stop 76 is moved to operative position under the control of a tabulator key 86 arranged in the keyboard of the machine. This key is carried by a key lever 87 which is fulcrumed near its rear end on a fulcrum bar 88. This key lever is connected to an upwardly extending bent link 89 which extends through an opening in the top plate and is connected at its upper end to the crank arm 84. A suitable returning spring 90 is connected to the key lever 87 in order to return said key lever and the parts connected therewith to normal position when the key 86 is released. An actuation of the tabulator key 86 is effective to operate the carriage release mechanism in the following manner: A bell crank lever 91 is pivoted on the pivot rod 23 and has a forwardly extending arm provided at its end with an off-set laterally projecting engaging portion 92, as shown in Fig. 2. This engaging portion 92 extends beneath the lever 87, so that the downward movement of said lever 87 is operative to actuate the lever 91. The depending arm of the lever 91 is connected to one end of a contractile spring 93, the opposite end of which is connected to a depending pin 94 carried by a fixed cross bar 95 secured to the frame of the machine. The lever 91 is provided with an elongated hub-like portion 96, and to the right-hand end of which is secured a depending crank arm 97. The arm 97 has an off-set laterally extending projection 98 at the end thereof which extends forward of the left-hand arm 65. The parts 91, 96 and 97 being rigidly connected together, it will be understood that a depression of the finger key 86 is effective to actuate the lever 91 and the crank arm 97 fixedly connected therewith. 120 This produces a rearward movement of the arm 97, thus actuating the associated arm 65 and the cross bar 64. The rearward movement of the cross bar 64, thus produced, is effective to operate the links 66, rock shaft 125 130

68, arm 70, link 71 and carriage releasing device 72, in order to elevate the feed rack 35 and disengage it from the carriage. When pressure on the key 86 is released the 5 returning spring 93 will return the lever 91 and the parts connected thereto to normal position. It will be understood, therefore, that an operation of the key 86 is effective to project the stop 76 controlled thereby into 10 the path of the engaging portions 46 of the column stops 45 and to simultaneously effect a release of the carriage.

It will be observed that the stop 76 is arranged at the forward side of the column 15 stop bar and moves rearwardly from the normal position to coöperate with the column stops 45, whereas the denominational stops 50 are arranged at the rear of the column stop bar 42 and move forwardly 20 from the normal position to coöperate with the column stops 43.

In addition to the column-to-column stop mechanism, and to the denominational selecting mechanism thus far described, I have 25 provided column selecting means which I will now describe.

The supporting plate 53 is secured to the base of the machine in the following manner: The upper threaded ends of two spin- 30 dles 99 are received in tapped openings in the base. Each of these spindles is pro- vided with an angular portion 100 by which the spindle may be turned to connect it to and disconnect it from the base of the ma- 35 chine. Each spindle extends through a hollow spacing sleeve or washer 101 which bears at its lower end against the supporting plate 53, the spindles themselves extending through openings in the plate. Those por- 40 tions of the spindles which are just beneath the plate 53 are threaded to receive nuts 102 by which the plate is secured in place be- 45 tween the nuts and the spacing sleeves 101 on the spindles 99. The lower end portion of each spindle 99 terminates in a pin 27, hereinbefore referred to, and to which a spring 26 is connected.

A sprocket wheel 103 is supported by a headed screw pivot 104 on the supporting 50 plate 53. A second sprocket wheel 105 is likewise supported by a headed screw pivot 106 on the supporting plate 53. A third sprocket wheel 107 is mounted to turn on an eccentric bearing portion 108 which is se- 55 cured by a screw 109 in the rotative position to which it may be adjusted, as in the construction disclosed in my application hereinbefore referred to. A fourth sprocket wheel 110 is detachably connected by suit- 60 able means, such as those described in my application hereinbefore referred to, to the lower end of a shaft 111 which receives a bearing at the lower end portion thereof in the supporting plate 53. This shaft extends 65 upwardly through an opening in the top

plate and carries a gear wheel 112 at the upper end thereof. The gear wheel has a long hub 113 by which the gear is secured to the shaft, the lower end of said hub bearing against the top plate to support the 70 shaft in place. A rack 114 is fixedly se- cured by screws 115 to the bracket arms 41 by which the column stop bar is secured to the carriage. This rack 114 meshes with the gear wheel 112 to effect a rotative movement 75 of the shaft 111 and the sprocket wheel 110 connected therewith. A sprocket chain, endless band or flexible stop carrier 116 passes around the sprocket wheels 103, 105, 107 and is engaged by the driving sprocket 80 wheel 110. One of the links of this endless sprocket chain is extended to form a travel- 85 ing stop 117 which, during the last half of the travel of the carriage from right to left moves in the direction of the arrow in Fig. 3, or from left to right, past the lower end portions of the series of stop levers 47 where the latter extend beneath the supporting plate 53. These contact portions of the le- 90 vers may be regarded as column selecting stops with which the traveling stop 117 co-acts, and each of which column selecting stops moves in a single path and to a single given extent. The chain in its passage from the sprocket wheel 105 to the sprocket wheel 95 103 is guided in and directed by a trough- 100 like guide 118 which is substantially U-shaped in cross section and has a flange 119 by which it is secured by headed clamp- 105 ing screws 120 to the bottom of the support- 100 ing plate 53. This guide is separated at its forward edge from the supporting plate so as to provide a space between the guide and plate through which the traveling stop 117 may pass in its movement from one sprocket 105 wheel 103 and 103 to the other and back again during the movement of the carriage. An actuation of one of the tabulator keys 54^a is effective, when the carriage reaches 110 about midway in the travel thereof, to inter- 110 pose the lower end of the associated stop lever 47 in the path of the approaching travel- 115 ing stop 117 for coöperation therewith. At the same time the carriage is released in the manner hereinbefore described and is ar- 115 rested through the coöperation of the trav- 120 eling stop 117 with the lower end of the key controlled stop lever which has been moved into the path thereof. If, for example, the column under the heading "P. pd." has been 120 filled in, and the operator desires to go at one operation to the column "H" under "Classification", the tabulator key 54^a under the index letter "H" on the tabulator scale is actuated and the corresponding stop lever 125 47 is moved to project the lower end thereof into the path of the traveling stop 117, and an arrest of the carriage will be effected when the traveling stop co-acts with the projected column selecting stop. 130

It is at times desirable to provide for denominational selection in the different columns selected with the aid of the traveling stop 117 and the key controlled column selecting stops. In order to bring about this result a number of column stops 43, corresponding to the number of columns which may be selected, are arranged on the column stop bar 42, one arranged in a position to correspond with the beginning of each of the columns which may be selected, as shown in Fig. 4. Ordinarily, an operation of one of the tabulator keys 54^a at this time would project the corresponding denominational stop in the path of the first of these column stops 43, thus arresting the carriage in a position other than that intended and preventing a proper selection of a column by the cooperation of the traveling stop 117 with the lower end of the actuated stop lever 47. In order to prevent this interference I have constructed a denominational stop mechanism so that it may, at will, be rendered inoperative or ineffective for denominational selection, so that the column selection may be attained without interference from the denominational selecting devices which are controlled by the same keys 54^a. The construction in question is as follows: The tabulator stop frame 49 is received in a cut-out or opening 121 in the rear edge of the top plate of the machine and is free to move therein fore and aft of the machine but is supported against movement in the direction of the travel of the carriage. The lower end of the frame 49 is supported on ball-like supporting pins 122 which extend upwardly from the base of the machine. These ball-like pivot pins are received in sockets 123 in the tabulator frame. In this manner a slight fore and aft pivotal movement of the frame around its supporting pins 122 may be effected. The extent of this movement in opposite directions is limited by screw pins 124 which project through openings 125 formed in depending ears 126 on the top plate of the machine. The screw pins 124 co-acting with the forward and rear walls of the openings 125 limit the fore and aft movement of the frame around its pivot pins 122. A contractile spring 127 has one end connected to a screw 128 secured to the tabulator frame 49, the opposite end of said spring being connected to a perforated bracket arm 129 secured to the top plate. The force of this spring is exerted to normally maintain the tabulator frame, and the denominational stops 50, in the forward or full line position, represented in Fig. 1. However, the frame and the denominational stops carried thereby may, when desired, be shifted to the dotted line position by means which will hereinafter be described. When the parts are shifted to the dotted line position, the projection of a denominational stop

by its key 54^a will be ineffective to bring said denominational stop into the path of the engaging portions 44 of the column stops 43. Denominational selection cannot therefore be effected at this time, and there will be no interference from the denominational selecting mechanism with the proper selection of the column by the coöperation of the column selecting stops at the lower ends of the levers 47 with the traveling stop 117.

The tabulator frame, together with the denominational stops, are moved to the dotted line position to render them ineffective by the following means: The tabulator frame has projecting forwardly therefrom arms 130 to which are secured, by screws 131, a frame comprising side arms 132 and a cross bar 133. This cross bar is arranged above the shift key levers 19 and 21 and in the rear of the pivot rod 23 thereof. A depression of either shift key is effective to elevate the cross bar 133, thereby turning the tabulator frame on its pivot supporting pins 122 to the position indicated by the dotted lines at the upper portion of the tabulator frame in Fig. 1, thus rendering the denominational stops ineffective.

While I have shown the tabulator frame controlled by the ordinary shift keys in the machine, in the present instance, it should be understood that any suitable means or key may be employed for this purpose. However, the shift keys in the present construction constitute a convenient means for shifting the tabulator frame 49, it, of course, being understood that the shift keys do not come into play for the ordinary functions for which they are provided during tabulating operations. The use of the shift keys, or either of them, for shifting the tabulator frame does not therefore interfere in any manner with the ordinary use of these keys to effect a case shifting movement of the platen.

The operation of the tabulator mechanism may vary under different conditions of use but as the same is shown set for use in connection with the blank A illustrated in Fig. 4 the operation is as follows: Assuming the carriage to be at the extreme right-hand position shown in Fig. 4, the operator proceeds at once to write the destination in the first column under the heading "Point." After this column is filled in the operator depresses the tabulator key 86 to interpose the stop 76 in the path of the first of the column stops 45, counting from the left, at the same time releasing the carriage. This will arrest the carriage at the beginning of the second column under the heading "Consignee" which may then be filled in. The operator again depresses the tabulator key 86, arresting the carriage at the beginning of the third column under the heading "Description." This column may then be filled

in. The next column under the heading "Weight" requires denominational selection and this is controlled by an actuation of a key 54^a which projects the proper 5 nominal stop in the path of the first of the column stops 43 counting from the left. The carriage having been arrested in the proper denominational position to write the amount under the heading "Weight" 10 this column may be filled in. The fifth column, under the heading "Rate," also requires a denominational arrest of the carriage which is controlled by a key 54^a actuating a denominational stop to arrest the 15 carriage at the proper denominational position. The next column under the heading "Freight" also requires denominational selection which is attained in the same manner by an actuation of one of the keys 54^a. 20 If an amount is to be "charged" a selecting key 54^a is actuated to arrest the carriage in the next column under the heading "Ogs." whereas, if cost of transportation is prepaid 25 the tabulator key 86 may be depressed to bring the stop 76 into the path of the third of the column stops 45 to arrest the carriage to write in the column under the heading "P.pd." thus skipping the column under the heading "Cgs." By this time the traveling stop 117 is brought to a position corresponding substantially to that shown in Fig. 3, where it is ready to co-act with the lower end of any of the stop levers which is projected into the path thereof, thus bringing 30 automatically the column selecting mechanism into use, such mechanism being controlled as hereinbefore explained by the same keys 54^a which control the denominational stops. Should the operator desire, 35 for example, to select the column under the heading "E" it is merely necessary to depress the shift key and actuate the key 54^a which is beneath the index letter "E" on the index plate. The effect of depressing 40 the shift key is, as hereinbefore explained, to render the denominational stops inoperative to co-act with any of the column stops 43. These column stops and the denominational stops will not therefore interfere with the free travel of the carriage, it 45 continuing its movement until arrested by the co-operation of the traveling stop 117 co-acting with the fifth stop lever 47 controlled by the actuated tabulator key 54^a. When 50 the carriage is arrested it will be in a position to begin writing in the first part of the column under the heading "E" on the blank A. If denominational selection within 55 the selected columnar field "E" is desired, the depressed shift key is released and the appropriate selecting key 54^a is actuated. This will be effective to project the corresponding denominational stop in the path of the next column stop 43 to arrest the 60 carriage at the selected denominational position.

sition within the column "E," as determined by the key 54^a which has been actuated. Any of the columns "A" "B" "C" "D" "E" "F" "G" "H" "I" "J" may be selected in a like manner by first depressing 70 a shift key and then actuating the proper tabulator key 54^a under the corresponding index letter on the tabulator scale, or index plate. After the last of the columns under the heading "Classification" has been filled 75 in, and the carriage brought to a position where the columns under the head of "Division" in the blank have been reached, the operator actuates one of the keys 54^a for denominational selection, since denominational 80 selection is to be effected first in the column under the heading "A" and next in the column under the heading "B." Denominational selection only can be attained in the columns under the headings "A" and "B" 85 since the traveling stop 117 travels beyond the last, or right-hand, stop lever 47 by the time the carriage reaches the line dividing the columns under the headings "J" and "A." On the other hand it will be understood 90 that column-to-column work only can be effected in the first three columns, and this only with the aid of the tabulator key 86. Denominational work only can be attained with the aid of the denominational 95 stops and the column stops 43 in the next three columns, and so on.

By my invention I provide tabulator mechanism which affords a wide variation of use, and a wide variation in the character 100 of tabulation which may be effected. Of course, it will be understood that different relative adjustments of the various stops enable the operator to provide different characters of tabulation at different portions of 105 the travel of the carriage, as may be required by the different characters of blanks employed. It will be understood that in the present blank, for example, the character thereof is such as to require a filling in of 110 the first six columns, whereas either the seventh or the eighth only need be filled in for each item. Moreover, only one, say, of the ten columns under the heading of "Classification" need be filled in for each item 115 120 or line. The item in one line may require the first of these columns under the heading "A," whereas, the item in the next line may require that the last of these columns under the heading "J" be filled in. The column 125 selecting mechanism coming into operation or use automatically when the carriage reaches the point where any of these columns under the heading "Classification" is to be filled in, greatly facilitates the operation of the machine. The operativeness of the construction to denominational select in each of the columns selected under the heading of "Classification" also greatly adds 130 to the effectiveness of the construction.

The tabulator mechanism in the present invention, as indicated above, is capable of a wide variation of uses and is particularly available in different classes of statistical work where an amount in money or tonnage is to be analyzed in a number of columns, such as foreign abstracting in auditors' offices where freight has traveled over several lines on a through rate and the total amount of the freight collected must be proportioned to different roads as in railroad freight billing, one example being illustrated in the foregoing description. The construction is also particularly available, for example, in the flour and feed business where different kinds of grain are handled such as wheat, oats, flour, bran, middlings, etc., and it is desirable to analyze the sales made to each customer for the purpose of keeping track of the merchandise sold each customer as well as to facilitate the keeping of a perpetual stock inventory. The construction is likewise available in the retail and wholesale coal business where the tonnage is kept by the different classes of coal. The merchants sell anthracite coal in four or five different sizes, as well as bituminous coal in four or five different grades; also slabs, sawed maple, etc., and in some cases cement and sewer pipe. Generally speaking, these firms make a daily recapitulation of the total of their sales by different classifications or commodities. They also recapitulate their sales under the various classifications showing the gross sales of each classification. With both or either of these forms it would be desirable to column select to the desired column and then decimal tabulate in that column somewhat in the manner hereinbefore described. In fact the mechanism of the present invention will be found very convenient in the average mercantile business where the analytical work will permit the form to be typewritten. The construction of the present invention is such that the parts may be readily arranged or adjusted to accommodate themselves to different requirements, or of the different characters of tabulating work indicated above. Various changes may be made without departing from the spirit and scope thereof.

What I claim as new and desire to secure by Letters Patent, is:—

1. In a typewriting machine, the combination of a carriage, an endless carrier which moves concurrently with the carriage, a stop carried by said carrier, stop devices coöperative with said stop, column stops, denominational stops coöperative with said column stops, and means operable at will for rendering said denominational stops inoperative to coöperate with said column stops.
2. In a typewriting machine, the combination of a carriage, an endless carrier which moves concurrently with the carriage, a

stop carried by said carrier, stop devices coöperative with said stop, column stops, denominational stops coöperative with said column stops, and key controlled means for moving said denominational stops to a position where said denominational stops when projected will be out of coöperative relation with said column stops. 70

3. In a typewriting machine, the combination of a carriage; and tabulating mechanism comprising denominational and column selecting devices controlled by the same keys, the keys being at all times operable for column selection at a given portion of the travel of the carriage, and key controlled means operable at will for rendering the denominational selecting devices ineffective. 75

4. In a typewriting machine, the combination of a carriage; and tabulating mechanism comprising normally operative denominational stop devices, normally operative column selecting stop devices, and key controlled means operable at will for rendering said denominational stop devices inoperative 80 so that the latter will not interfere with said column selecting devices operating properly for the selection of columns. 85

5. In a typewriting machine, the combination of a carriage; tabulating mechanism including column and denominational selecting means, said mechanism comprising means whereby the mechanism is operative for column selection only at a given portion of the travel of the carriage; and key controlled means operable at will for rendering said mechanism inoperative for denominational selection, so as not to interfere with the use of the mechanism for column selection. 95

6. In a typewriting machine, the combination of a carriage; tabulating mechanism including column and denominational selecting means, said mechanism comprising means whereby the mechanism is operative 100 for column selection only at a given portion of the travel of the carriage; and key controlled means operable at will for rendering said mechanism inoperative for denominational selection, so as not to interfere with the use of the mechanism for column selection. 105

7. In a typewriting machine, the combination of a carriage; and tabulating mechanism including means by which denominational selection only may be obtained at one part of the travel of the carriage, by which column selection can be obtained only at another portion of the travel of the carriage, and by which denominational selection in a selected columnar field may be obtained, said means including key controlled means operable at will for rendering the mechanism inoperative for denominational selection and so maintaining it indefinitely 110 115 120 125

and without interfering with the operativeness of the mechanism for column selection.

8. In a typewriting machine, the combination of a carriage; and tabulating mechanism including means by which denominational selection only may be obtained at one part of the travel of the carriage, by which column selection can be obtained only at another portion of the travel of the carriage, and by which denominational selection in a selected columnar field may be obtained, said means including normally effective denominational selecting devices, a traveling stop, column selecting devices which at all times may be projected into coöperative relation with the traveling stop, and key controlled means operable at will for rendering said denominational selecting devices ineffective.

20 9. In a typewriting machine, the combination of a carriage; and tabulating mechanism including a traveling stop movable in one path, column selecting stops at all times projectable into the path of said traveling stop, a series of traveling column stops which move in a different path from said first mentioned stop, denominational selecting stops that normally may be projected into the path of said column stops, and means operable at will for moving said denominational selecting stops to a position where they are ineffective when projected to co-act with said column stops.

35 10. In a typewriting machine, the combination of a carriage; and tabulating mechanism including a traveling stop movable in one path, column selecting stops at all times projectable into the path of said traveling stop, a series of traveling column stops which move in a different path from said first mentioned stop, denominational selecting stops that normally may be projected into the path of said column stops, means operable at will for moving said denominational selecting stops to a position where they are ineffective when projected to co-act with said column stops, and a set of keys for controlling said column selecting and denominational selecting stops.

40 11. In a typewriting machine, the combination of a carriage; and tabulating mechanism including a traveling stop movable in one path, column selecting stops at all times projectable into the path of said traveling stop, a series of traveling column stops which move in a different path from said first mentioned stop, denominational selecting stops that normally may be projected into the path of said column stops, means operable at will for moving said denominational selecting stops to a position where they are ineffective when projected to co-act with said column stops, and a set of keys for controlling said column selecting and de-

nominational selecting stops, each of said 65 keys being operative to simultaneously project a column selecting and a denominational selecting stop.

12. In a typewriting machine, the combination of a carriage, two stop carriers one 70 carried by the carriage and the other separate from but connected to be moved by the carriage, a stop carried by each of said carriers, key controlled means coöperative with one or the other of said stops depending on 75 the position of the carriage in its line of travel, and key controlled means operable at will on said first key controlled means to render the same ineffective to coöperate with the stop on the carriage.

80 13. In a typewriting machine, the combination of a carriage, two traveling stops which are moved by the carriage and are separated and have separate fixed paths of movement, a key controlled stop member 85 that is moved at each operation into the paths of both traveling stops, and key controlled means operable at will on said stop member to render it ineffective to co-act with one of said traveling stops.

90 14. In a typewriting machine, the combination of a carriage, two traveling stops which are moved by the carriage and are separated and have separate fixed paths of movement, a series of key controlled stop 95 members each movable at an operation thereof into the paths of both traveling stops, and key controlled means operable at will on said stop members to render them ineffective to co-act with one of said traveling stops.

100 15. In a typewriting machine, the combination of a carriage, key controlled tabulator stops which are spaced apart at given intervals, key controlled stops which are spaced apart at different intervals from said 105 first mentioned stops, a traveling stop which moves in one path and with which said first mentioned key controlled stops coöperate, a second traveling stop which travels in a different path from the other traveling stop 110 and with which said second mentioned key controlled stops coöperate, and key controlled means operable at will for rendering said first mentioned key controlled stops ineffective to co-act with the associated traveling stop.

115 16. In a typewriting machine, the combination of a carriage, key controlled tabulator stops which are spaced apart at given intervals, key controlled stops which are spaced 120 apart at different intervals from the first mentioned stops, a traveling stop which moves in one path and with which said first mentioned key controlled stops coöperate, a second traveling stop which travels in a different path from the other traveling stop and with which said second mentioned key controlled stops coöperate, the keys which con-

trol the said first mentioned stops also controlling the second key controlled stops, and key controlled means for rendering the first mentioned key controlled stops ineffective to 5 co-act with the associated traveling stop.

17. In a typewriting machine, the combination of a carriage, a series of key controlled devices spaced apart differently at different portions thereof, stops which travel 10 in different paths, a stop traveling in one path coöperating with those portions of the key controlled devices which have one character of spacing and another stop traveling in a different path coöperating with those 15 portions of said devices which have a different character of spacing, and means operable at will on said key controlled devices for rendering them ineffective on one of said traveling stops without affecting the oper- 20 ativeness thereof on the other traveling stop.

18. In a typewriting machine, the combination of a carriage, key controlled stop devices spaced apart at one portion thereof at letter space intervals and spaced apart at 25 another portion thereof at a plurality of letter space intervals, a traveling stop co- operative with those portions of said devices which have one character of spacing, a second traveling stop which cooperates with 30 those portions of said devices which are differently spaced, and means operable at will on said key controlled stop devices for rendering them ineffective on one of said traveling stops.

35 19. In a typewriting machine, the combination of a carriage, key controlled stops which are spaced apart at letter space intervals and constitute denominational stops, key controlled stops which are spaced apart 40 at a plurality of letter space intervals and constitute column selecting stops, a traveling stop with which the denominational stops co- operate, a second traveling stop which travels in a different path from said first mentioned 45 traveling stop and with which the column selecting stops are coöperative, and key controlled means operative at will on said de- 50 nominational stops to render them ineffective to coöperate with the traveling stop with which they normally co-act.

20. In a typewriting machine, the combination of a carriage, key controlled stops which are spaced apart at letter space intervals and constitute denominational stops, 55 key controlled stops which are spaced apart at a plurality of letter space intervals and constitute column selecting stops, a traveling stop with which the denominational stops co- operate, a second traveling stop which travels 60 in a different path from said first mentioned traveling stop and with which the column selecting stops are coöperative, the keys which control the denominational stops also controlling the column selecting stops, and

means operable at will on certain of said 65 key controlled stops to render them ineffect- 70ive to co-act with the traveling stop with which they are normally coöperative.

21. In a typewriting machine, the combination of a carriage, a series of key con- 75 trolled levers pivoted intermediate the ends thereof, a traveling tabulator stop having a path of movement transversely of said levers and at one side of the pivotal centers thereof and with which said levers are co- 80 operative to arrest the carriage, a second traveling tabulator stop having a path of movement transversely of said levers and at the opposite side of the pivotal centers thereof and with which said levers are coöperative 85 to arrest the carriage, and means operative on said levers to render them ineffective on one of said traveling stops.

22. In a typewriting machine, the combination of a carriage, a series of key con- 85 trolled levers pivoted intermediate the ends thereof, the spacing between said levers at one side of the pivotal centers thereof being different from what it is at the opposite side of the pivotal centers of said levers, a travel- 90 ing tabulator stop having a path of move- ment transversely of said levers and at one side of the pivotal centers thereof and with which said levers are coöperative to arrest the carriage, a second traveling tabulator 95 stop having a path of movement trans- versely of said levers and at the opposite side of the pivotal centers thereof and with which said levers are coöperative to arrest the carriage, and key controlled means op- 100 erable at will on said key controlled levers to render them ineffective on one of said traveling stops.

23. In a typewriting machine, the combination of a carriage, a series of key con- 105 trolled levers pivoted intermediate the ends thereof, said levers at one side of the pivotal centers thereof being spaced apart at letter space intervals to form denominational stops, the levers at the opposite side of the 110 pivotal centers being spaced apart at a plu- rality of letter space intervals to form col- umn selecting stops, a plurality of traveling stops with each of which the denominational stops are coöperative, a traveling stop with 115 which said column selecting stops are coöperative, and means operable at will for ren- dering the denominational stops ineffective to coöperate with the traveling stops with which they normally co-act.

24. In a typewriting machine, the combination of a carriage, a series of key con- 120 trolled levers pivoted intermediate the ends thereof, a traveling tabulator stop having a path of movement transversely of said le- 125 vers and at one side of the pivotal centers thereof and with which said levers are co- operative to arrest the carriage, a second

traveling tabulator stop having a path of movement transversely of said levers and at the opposite side of the pivotal centers thereof and with which said levers are co-
operative to arrest the carriage, carriage releasing means which are operated to release the carriage when any of said key controlled levers is actuated, and means operable at will on said key controlled levers to render them ineffective to co-act with one of said traveling stops.

25. In a typewriting machine, the combination of a carriage, a series of key controlled levers pivoted intermediate the ends thereof, said levers at one side of the pivotal centers thereof being spaced apart at letter space intervals to form denominational stops, the levers at the opposite side of the pivotal centers being spaced apart at a plurality of letter space intervals to form column selecting stops, a plurality of traveling stops with each of which the denominational stops are co-operative, a traveling stop with which said column selecting stops are co-operative, carriage releasing means which are operated to release the carriage when any of said key controlled levers is actuated, and means operable at will on said key controlled levers to render the denominational stops ineffective on the plurality of traveling stops with which they normally co-operate.

26. In a typewriting machine, the combination of a carriage, a column stop bar carried thereby, a series of column stops carried by said stop bar, a series of key controlled denominational stop carrying levers, the denominational stops being moved by said levers into co-operative relation with said column stops, a traveling tabulator stop which is moved by the carriage and travels in a different path from said column stops and into the path of which each of said levers is adapted to be moved, and means operative at will on said key controlled levers for rendering the denominational stops ineffective to co-operate with said column stops.

27. In a typewriting machine, the combination of a carriage, a column stop bar carried thereby, a series of column stops carried by said bar, a series of key controlled denominational stop carrying levers, the denominational stops being normally moved by said levers into co-operative relation with said column stops, a traveling tabulator stop which is moved by the carriage and travels in a different path from said column stops and into the path of which each of said levers is adapted to be moved, means which afford an adjustment of the column stops along said bar, means which afford an adjustment of the traveling tabulator stop relatively to the carriage, and

means operable at will on said key controlled levers for rendering the denominational stops ineffective to co-act with said column stops.

28. In a typewriting machine, the combination of a carriage, a column stop bar carried thereby, a series of column stops carried by said stop bar, a series of key controlled denominational stop carrying levers, the denominational stops being normally moved by said levers into co-operative relation with said column stops, an endless band driven by the carriage, a tabulator stop carried by said endless band and with which said levers are co-operative to arrest the carriage, and means operable at will on said denominational stops to render them ineffective to co-operate with the column stops.

29. In a typewriting machine, the combination of a carriage, a column stop bar carried thereby, a series of column stops carried by said stop bar, a series of key controlled denominational stop carrying levers, the denominational stops being normally moved by said levers into co-operative relation with said column stops, an endless band driven by the carriage, a tabulator stop carried by said endless band and with which said stop levers are co-operative to arrest the carriage, and key controlled means operable at will for effecting a shifting movement of said denominational stops to a position where when any of them is projected it will be inoperative to co-act with the column stops, the shifting of the denominational stops to ineffective position being produced without affecting the operativeness of the key controlled levers to co-act with the tabulator stop carried by the endless band.

30. In a typewriting machine, the combination of a carriage, a column stop bar carried thereby, a series of column stops carried by said stop bar, a series of key controlled denominational stop carrying levers, the denominational stops being normally moved by said levers into co-operative relation with said column stops, a traveling tabulator stop which is moved by the carriage and travels in a different path from said column stops and into the path of which each of said levers is adapted to be moved, means which afford an adjustment of the column stops along said bar, means which afford an adjustment of the traveling tabulator stop relatively to the carriage, and key controlled means operable at will for effecting a shifting movement of said denominational stops to a position where when any of them is projected it will be inoperative to co-act with the column stops, the shifting of the denominational stops to ineffective position being produced without affecting the operativeness of the key controlled levers to co-act with the traveling tabulator stop.

- thereof and with which said levers are operative to arrest the carriage, and key controlled means operable at will for effecting a shifting movement of said levers to a position where when any of them is projected it will be inoperative to co-act with one of said traveling stops but will be operative to co-act with the other of said traveling stops.
37. In a typewriting machine, the combination of a carriage, key controlled stops which are spaced apart at letter space intervals and constitute denominational stops, key controlled stops which are spaced apart at a plurality of letter space intervals and constitute column selecting stops, a traveling stop with which the denominational stops normally coöperate, a second traveling stop which travels in a different path from said first mentioned traveling stop and with which said column selecting stops are co-operative, the keys which control the denominational stops also controlling the column selecting stops, and key controlled means operable at will for effecting a shifting movement of the denominational stops to a position where when any of them is projected it will be inoperative to co-act with the traveling stop with which it is normally coöperate, the shifting of the denominational stops to ineffective position being produced without affecting the operativeness of the column selecting stops.
38. In a typewriting machine, the combination of a carriage, key controlled stops which are spaced apart at letter space intervals and constitute denominational stops, key controlled stops which are spaced apart at a plurality of letter space intervals and constitute column selecting stops, a traveling stop with which the denominational stops normally coöperate, a second traveling stop which travels in a different path from said first mentioned traveling stop and with which the column selecting stops are co-operative, and key controlled means operable at will for effecting a shifting movement of said denominational stops to a position where when any of them is projected it will be ineffective to coöperate with the traveling stop with which the denominational stops normally co-act, the shifting of the denominational stops to ineffective position being produced without affecting the operativeness of the column selecting stops.
39. In a typewriting machine, the combination of a carriage, key controlled stop devices spaced apart at one portion thereof at letter space intervals and spaced apart at other portions thereof at a plurality of letter space intervals, a traveling stop co-operative with those portions of said devices which have one character of spacing, a second traveling stop which coöperates with

those portions of said devices which are differently spaced, and key controlled means operable at will for effecting a shifting movement of said key controlled stop devices to a position where when any of them is projected it will be ineffective to co-act with one of said traveling stops but will be effective to co-act with the other of said traveling stops.

40. In a typewriting machine, the combination of a carriage, a series of key controlled devices spaced apart differently at different portions thereof, stops which travel in different paths, a stop traveling in one path coöperating with those portions of the key controlled devices which have one character of spacing, and another stop traveling in a different path coöperating with those portions of said devices which have a different character of spacing, and key controlled means operable at will for effecting a shifting movement of said key controlled devices to a position where when any of them is projected it will be ineffective to co-act with one of said traveling stops but will be effective to co-act with the other of said traveling stops.

41. In a typewriting machine, the combination of a carriage, key controlled tabulator stops which are spaced apart at given intervals, key controlled stops which are spaced apart at different intervals from the first mentioned stops, a traveling tabulator stop which moves in one path and with which the first mentioned key controlled stops coöperate, a second traveling stop which travels in a different path from the other traveling stop and with which said second mentioned key controlled stops coöperate, the keys which control the first mentioned stops also controlling the second key controlled stops, and key controlled means operable at will for effecting a shifting movement of the first mentioned key controlled stops to a position where when any of said stops is projected it will be inoperative to co-act with the traveling stop with which it normally coöperates.

42. In a typewriting machine, the combination of a carriage, key controlled tabulator stops which are spaced apart at given intervals, key controlled stops which are spaced apart at different intervals from said first mentioned stops, a traveling stop which moves in one path with which said first mentioned key controlled stops normally coöperate, a second traveling stop which travels in a different path from the other traveling stop and with which said second mentioned key controlled stops coöperate, and key controlled means operable at will for effecting a shifting movement of said first mentioned key controlled stops to a position where when any of them is pro-

jected it will be ineffective to co-act with the traveling stop with which it normally co-acts, the shifting movement of the first mentioned key controlled stops to ineffective position being produced without affecting the operativeness of the second mentioned key controlled stops to coöperate with the traveling stop with which they co-act.

43. In a typewriting machine, the combination of a carriage; and tabulating mechanism including a column-to-column tabulator device for arresting the carriage at one column and then at the next, independently operable column selecting devices, denominational selecting devices, and keys each operative to project both a column selecting device and a denominational selecting device, whereby the carriage may be arrested first at one column and then at the next, whereby column selection may be effected, and whereby denominational selection in different columns may be effected.

44. In a typewriting machine, the combination of a carriage; and tabulating mechanism including a column-to-column tabulator device for arresting the carriage at one column and then at the next, independently operable key controlled column selecting devices, and other key controlled denominational selecting devices, whereby the carriage may be arrested first at one column and then at the next, whereby column selection may be effected, and whereby denominational selection in different columns may be effected, the same keys which control the column selecting devices also controlling the denominational selecting devices.

45. In a typewriting machine, the combination of a carriage; tabulating mechanism including a column-to-column tabulator device for arresting the carriage at one column and then at the next, independently operable column selecting devices, and denominational selecting devices, whereby the carriage may be arrested first at one column and then at the next, whereby column selection may be effected, and whereby denominational selection in different columns may be effected; and key-controlled means for rendering the denominational selecting devices ineffective for denominational selection.

46. In a typewriting machine, the combination of a carriage; tabulating mechanism including a column-to-column tabulator device for arresting the carriage first at one column and then at the next, independently operable key controlled column selecting devices, and key controlled denominational selecting devices; whereby the carriage may be arrested first at one column and then at the next, whereby column selection may be effected, and whereby denominational selection in different columns may be effected, and key-controlled means for

dering the key controlled means for the denominational selecting devices ineffective for denominational selection.

47. In a typewriting machine, the combination of a carriage; and tabulating mechanism including a column-to-column tabulator device for arresting the carriage first at one column and then at the next, independently operable column selecting devices, denominational selecting devices, column stops which have one path of movement and with which said column-to-column device co-acts, column stops which have a different path of movement and with which the denominational selecting devices co-act, and a traveling stop having a third path of movement and with which said column selecting devices co-act, whereby the carriage may be arrested first at one column and then at the next, whereby column selection may be effected, and whereby denominational selection in different columns may be effected.

48. In a typewriting machine, the combination of a carriage; and tabulating mechanism including a column-to-column tabulator device for arresting the carriage first at one column and then at the next, independently operable column selecting devices, other denominational selecting devices, and a carriage releasing means controlled by all of said devices, a column selecting device and a denominational selecting device being both projected to operative position at each actuation of a tabulator key, whereby the carriage may be arrested first at one column and then at the next, whereby column selection may be effected, and whereby denominational selection in different columns may be effected.

49. In a typewriting machine, the combination of a carriage; and tabulating mechanism including a column-to-column tabulator device for arresting the carriage first at one column and then at the next, independently operable column selecting devices, denominational selecting devices, column stops which have one path of movement and with which said column-to-column device co-acts, column stops which have a different path of movement and with which the denominational selecting devices co-act, a traveling stop having a third path of movement and with which said column selecting devices co-act, and carriage releasing means controlled by all of said devices, whereby the carriage may be arrested first at one column and then at the next, whereby column selection may be effected, and whereby denominational selection in different columns may be effected.

50. In a typewriting machine, the combination of a carriage, a traveling stop which moves in one direction during the travel of the carriage in the direction of its feed.

- second traveling stop which moves in the opposite direction at this time, a key controlled stop coöperative with said first mentioned traveling stop, a key controlled stop coöperative with said second traveling stop, and key controlled means operable at will on one of said key controlled stops to render it ineffective to coöperate with the traveling stop with which it co-acts.
51. In a typewriting machine, the combination of a carriage, two stop carriers adapted to move in unison with the carriage, a stop carried by each of said carriers, a key controlled stop member coöperative when projected first with one and then with the other of said first mentioned stops depending on the position of the carriage, and key controlled means operable at will on said key controlled stop member to render it ineffective to coöperate with one of said first mentioned stops.
52. In a typewriting machine, the combination of a carriage, a column stop bar, column stops carried by and projecting from opposite sides of said bar, a single key controlled stop coöperative at all times when projected only with those column stops that project from one side of the stop bar and having only a single extent of movement to operative position, and a separate key controlled stop coöperative only with those column stops that project from the opposite side of the stop bar and having only a single given extent of movement to operative position.
53. In a typewriting machine, the combination of a carriage, a column stop bar, column stops carried by and projecting from opposite sides of said bar, a key controlled stop coöperative at all times when projected only with those column stops that project from one side of the stop bar and having only a single extent of movement to operative position, and key controlled denomina-
- tional stops each coöperative only with those column stops which project from the opposite side of said bar.
54. In a typewriting machine, the combination of a carriage, a column stop bar, column stops carried by and projecting from opposite sides of said bar, a key controlled stop coöperative at all times when projected only with those column stops that project from one side of the stop bar, said key controlled stop moving into and out of operative position in a single path only and to a single given extent only, and a separate key controlled stop coöperative only with said column stops that project from the opposite side of the stop bar, said second key controlled stop moving into and out of operative position in a single path only and to a single given extent only.
55. In a typewriting machine, the combination of a carriage, a column stop bar, column stops carried by and projecting from opposite sides of said bar, a key controlled stop coöperative at all times when projected only with those column stops that project from one side of the stop bar, said key controlled stop moving into and out of operative position in a single path only and to a single given extent only, and a series of key controlled denominational stops each coöperative only with those column stops which project from the opposite side of the stop bar, and each of which denominational stops moves only in a single path and to a single given extent.

Signed in the borough of Manhattan, city 30 of New York, in the county of New York, and State of New York, this 26th day of January, A. D. 1914.
